UNITED STATES PATENT OFFICE.

BROR M. LOFQUIST, OF FITCHBURG, MASSACHUSETTS.

DIE-SINKER'S VISE.

Application filed August 18, 1925. Serial No. 51,022.

This invention relates to a vise particularly adapted for the purposes of the die sinker but capable of other uses.

The principal objects of the invention are 5 to provide work holding jaws supported on a spherical joint so that it can be tipped up to slight angles very readily and by removing a simple element can be tipped up about the same horizontal axis to a 45 degree 10 angle or over; to provide a construction by which with a similar change the holder can be tipped about a transverse axis and securely held; to provide a convenient scale for showing the angle at which the vise is 15 tipped about one axis; to provide a set of additional jaws for use on work that would not go between the ordinary stationary jaws; and to provide a modified form in which the vise can be tipped up as far as 90° and 20 can also be tipped to 45° about a transverse axis.

Other objects and advantages of the invention will appear hereinafter.

Reference is to be had to the accompanying drawings in which—

Fig. 1 is a plan of a vise constructed in accordance with this invention and showing the extra pair of jaws thereon;

Fig. 2 is a side view showing in dotted lines the work-holding jaws tilted to about an angle of 45° and showing in full lines the horizontal position of these jaws with the extra jaws in position;

Fig. 3 is an end view of the scale for showing the angle;

Fig. 4 is a sectional view on the line 4—4 of Fig. 1;

Fig. 5 is a side view partly in the same central section with the parts extended and 40 shown out of contact with each other;

Fig. 6 is a view similar to Fig. 2 of a modification;

Fig. 7 is a plan thereof; and

Fig. 8 is a sectional view of the same on 45 the line 8—8 of Fig. 6.

Referring to the first two sheets of drawings, I have shown the invention in a form comprising a base 10 which may be made of one solid piece or two but is provided with 50 a recess 11 therein for a nut 12 on a vertical fastening bolt 13. This base is provided with a concave spherical seat or bearing 15 in the top arranged horizontally for supporting a hemispherical jaw support 16 and 55 allowing the same to swing in this socket to all angles and in all practical directions.

It will be noticed that the recess 11 extends in more than half way and that the fastening bolt 13 is located permanently at the center and in line with the vertical central axis of the whole device. It projects through a space 17 of conical form, or at least of tapering form, in the support 16.

The support 16 is free to turn in its seat 15 as far as this space 17 will allow it to 65 turn. This space may be shaped as shown in the plan or otherwise to provide the adjustments desired. The bolt 13 extends freely up through this space and screws into a hole provided in a hemispherical nut 18 having a beveled top (shown in Fig. 4) which fits in a hemispherical seat or recess 19 in the top of the support 16. This bolt 70 obviously is held in stationary position and the nut 18 is incapable of turning about any horizontal axis but can turn only about the vertical axis of this bolt. When the nut 12 is tightened up, the support 16 is fixed in 75 whatever position it is in at that time.

On the top the base 10 is provided with a flange 20 of circular shape extending inwardly and having an inner edge 21 concentric with the spherical seat 15 so that the holder 16 has further support at the top of the base 10. This surface 21 really constitutes part of that seat. It will be noticed that the bottom part of the seat 15 is circular in form and extends only part way up to the flange 20. In other words, there is a space 22 here which extends all the way 80 around and is provided for certain purposes as will appear.

On the top of the flange 20 are located a pair of opposite open top bearings 23. These bearings support a pair of center pins 95 or journals 24 and 25. The journals preferably are semi-cylindrical in shape or as shown they occupy more than half a cylinder and are flat on top. Each one of them is secured independently in position on the top of the support 16 by a screw 29 and they rest on these open top bearings. The axis of the shaft constituted by these two journals is called the longitudinal axis of the device. It will be observed that the support 16 can 100 turn on the shaft 24—25 through a certain angle. This is limited by a pair of jaws 26 which are fixedly mounted on the top of the support 16 and at opposite sides thereof. These jaws are fixed on the support in 105 any desired way but they are provided with rows of screws 27 which are adapted to be 110

projected through the jaws to hold the work between them and as each screw can be adjusted independently they will conform to any irregularities in the surface of the work. The drawings do not show these screws as holding the work but that will be obvious.

As so far described, the jaws 26 can be tipped up about the longitudinal axis only to such position as is possible due to the limitation of the flange 20 at the bottom. One jaw will eventually touch on the flange 20 and thus limit it but this flange 20 is provided with a separable piece 20^a which is a continuation of the flange but is held in place by screws 28. This part of the flange therefore can be taken off as shown in Fig. 2 and the jaw 26 will then be capable of being swung down into the recess 22 so as to get an adjustment up to about a 45° angle 20 as shown in dotted lines in Fig. 2. On the end of one of the center pins 24 is fixed a metal plate 30 concentric with the stud and having a scale around it to indicate the angle to which the support is turned. A stationary pointer 31 is provided on the base 10 for indicating this angle on the scale. The nut 18 is spaced from a plate 33 which covers it.

In case it is desired to hold a piece of work W which is wider than the space between the jaws 26 I hold in that space another pair of Z-shaped jaws 36 by introducing the screws 27 into flanges in the bottoms of the jaws 36, which jaws rest on the tops of the jaws 26. These jaws 36 are made the same way, having screws 37 for directly engaging the work.

I have now described the method of tilting the work holding jaws about what I have called the longitudinal axis. When it is desired to tilt them about a transverse axis, the centerpin 25 is removed by taking out the screw that holds it and the piece 20^a is removed. Then the whole support can 45 be swung down as shown in Fig. 4, about a transverse axis and adjusted there. The adjustment is limited only by the width of the spaces 17 and 22.

From what has been said, it will be obvious that this vise can be tilted to any angle that is likely to be desired universally in two planes and yet the mechanism is comparatively simple and the adjustments are easily made.

As a convenient way of holding the jaws exactly in horizontal position, I can put solid pieces 35 under the two jaws 26 as shown in Fig. 2.

Referring to the last sheet of drawings, I have shown the invention in a form in which the vise is made so that the holder can be swung all the way from zero to 90° and also swung on a transverse axis in a certain way. In this case the base 40 is provided with a slot 41 and a nut 42 therein on a bolt 43 at

a 30° angle or thereabouts. This bolt engages a nut 44 and holds the hemispherical jaw support 46 in the same way as in the other case. This base has a perforation 45 for the bolt 43.

In this case two jaws 47 and 48 are mounted on the jaw support in a manner such as described before. This support is pivoted on two center pins 49 as in the other case. The bolt 43 can be located in a slot 50 in the form of a cross for the purpose of tipping in both directions. The sides of the slot 50 are at approximately 90 degrees to each other. This enables the support 46 to swing approximately 90 degrees about the bolt 43.

In the full line position shown in Figs. 6, 7 and 8 the support 46 can be turned about the axis of the pins 49, that is the longitudinal axis, all the way around to 90° as shown in dotted lines. But when in the 45° position, it can be tilted back 45° on a transverse axis by removing the rear center pin 49, otherwise it is not necessary to describe the details of this arrangement.

It will be seen that in both constructions, a very wide degree of adjustment is secured in a very simple manner and in fact the adjustment is practically universal and yet the mechanism is simple and inexpensive. The adjustments are made easily and any die sinker will be able to understand the machine without any trouble.

Although I have illustrated and described only two forms of the invention, I am aware of the fact that modifications can be made therein by any person skilled in the art without departing from the scope of the invention as expressed in the claims. Therefore, I do not wish to be limited to all the details of construction herein shown and described, but what I do claim is:—

1. In a vice, the combination of a base having a spherical seat, a support for a pair of jaws having a spherical bottom universally adjustable on said seat, a bolt extending through the base and support for holding the latter in its adjusted positions, a hemi-spherical nut adjustable about the diametrical center of said support, said support having a pair of center pins projecting from opposite ends in diametrical alinement, bearings on the base for said center pins to permit adjustment about their axis, and means whereby one of said center pins can be removed to permit adjustment about a diametrical axis.

2. In a vice, the combination of a base, a hemi-spherical support tiltingly adjustable thereon, a pair of jaws on the support projecting from it on the opposite sides of a diametrical plane, and means for holding the support in adjusted positions around its center, said base having a removable flange below which the jaw on one side is not adapted to descend, and having a space

therein below the flange for receiving said jaw when the flange is removed to permit adjustment to a greater angle.

3. In a die sinker's vise, the combination of a base, a universally adjustable spherical support thereon having a pair of jaws projecting at opposite sides, and means for holding the support in adjusted positions around its center, said base having flanges at the top engaging the exterior of the support and a space therein under said flanges, one flange being removable to permit adjustment of one jaw below the top of the base.

15 4. In a die sinker's vise, the combination of a base, a universally adjustable spherical support thereon having a pair of jaws projecting at opposite sides, means projecting into the support from the base for holding the support in adjusted positions around its center, said base having a space therein for receiving one of said jaws to permit adjustment of one jaw below the top of the base, and an extra pair of Z-shaped jaws mounted 25 on the first-named jaws to take in a wider piece of work.

5. In a vise, the combination of a base having a central perforation and a seat, a support mounted for universal adjustment in said seat, a pair of jaws on said support, a pair of diametrically opposite center pins projecting from said support, a pair of bearings on the base for supporting the center pins and permitting adjustment of the support around the center pins as a diametrical axis, the support having a spherical seat at its center, a circular nut universally adjustable in the last-named seat, and a bolt extending up through the central perforation 30 of the base and through the support for entering said nut and holding the support in any position to which it may be adjusted, the base having a flange around it fitting the spherical surface of the support, part of 35 said flange being removable to permit one jaw on the support to descend below it.

40 6. In a die sinker's vise, the combination of a base having a central vertical perfora-

tion and a concentric spherical seat, a spherical support mounted for universal adjustment in said seat projecting upwardly therefrom, a pair of jaws on said support, a pair of diametrically opposite center pins projecting from said support, a pair of bearings on the base for supporting the center pins 50 and permitting adjustment of the support around the center pins as a diametrical axis, a semicircular scale on the end of one of said center pins, a pointer on the base registering with said scale to show the angle of 55 adjustment, the support having a spherical seat at its center, a circular nut universally adjustable in the last-named seat, and a bolt extending up through the central perforation of the base and through the support for 60 entering said nut and holding the support in any position to which it may be adjusted, the base having a flange around it fitting the spherical surface of the support, part of 65 said flange being removable to permit one jaw on the support to descend below it, one of said center pins being removable to permit the support to be adjusted about a different axis.

7. In a vise, the combination of a base 75 having a central vertical perforation and a concentric spherical seat, a spherical support mounted for universal adjustment in said seat projecting upwardly therefrom, a pair of center pins projecting diametrically 80 from opposite sides of said support, a pair of bearings on the base for supporting the center pins and permitting adjustment of the support around the center pins as a diametrical axis, a bolt extending up through 85 the central perforation of the base and through the support for holding the support in any adjusted position, one of said center pins being removable to permit the support to be adjusted about a different 90 axis, and a pair of jaws mounted on the support.

In testimony whereof I have hereunto affixed my signature.

BROR M. LOFQUIST.
